DEFLECTING PLATE FOR CATHODE RAY
TUBESRobert E. Rutherford, Rutherford, N. J., assignor
to Allen B. Du Mont Laboratories, Inc., Passaic,
N. J., a corporation of Delaware

Application May 29, 1942, Serial No. 444,962

2 Claims. (Cl. 250—159)

This invention relates to deflecting plates for cathode ray tubes. One of the objects of the invention is to produce such plates so that there are no rough or irregular edges thereon that would tend to distort the electron beam. Another object is to construct and mount the plates in such a way that they maintain their exact shape and relative positions with respect to each other and are free from vibration. Another object is to make the plates very stiff and rigid without interfering with the usual functioning of the same. Other objects will be apparent as the description proceeds.

Heretofore, deflecting plates for cathode ray tubes have been made of thin sheets cut from larger sheets. The result has often been that when these plates were installed they were warped or bent or became displaced with respect to each other, thus resulting in lack of symmetry. Besides, the cut edges were often left rough or with small projections thereon which caused irregularities in the electrostatic field when the plates were energized.

By the present invention deflection plates are made that are free from burrs or rough or irregular spots along the edges thereof, the diverging angle between the plates as well as the distance between the plates where they are installed is accurately controlled and retained, and the plates themselves are made very rigid, thus preventing unwanted bending or distortion thereof.

The invention will be understood from the description in connection with the accompanying drawing, in which:

Fig. 1 is a plan view of an illustrative embodiment of the invention;

Fig. 2 is a side view thereof;

Fig. 3 is a similar side view, taken at right angles to Fig. 2;

Fig. 4 is a plan view on an enlarged scale of one of the plates; and

Fig. 5 is a section along the line 5—5 of Fig. 4. In the drawing, reference characters 1, 2, 3 and 4 indicate metal rods of the usual sort that are to be electrically connected through a press (not shown) and secure or hold in place deflecting plates for a cathode ray tube, and also to make electrical connection thereto.

Insulating tubes 5 and 6 of ceramic or other suitable material are mounted on the rods 1 and 2. Metal straps 7, 8 and 9 are attached to the ceramic tubes 5 and 6 to keep the grid 10 and anodes 11

and 12 in place. Mica discs 14 and 15 are provided with holes having eyelets therein so that the rods 1, 2, 3 and 4 can pass therethrough and support these discs at fixed distances apart.

5 A pair of deflecting plates 16 and 17 and another pair of deflecting plates 18 and 19 at right angles to the first pair are mounted upon the rods or supports 1, 2, 3 and 4, and upon the auxiliary short supports 20, 21, 22 and 23, the auxiliary supports being attached to the discs 14 and 15 by eyelets in the usual way.

One of the deflecting plates 17 is shown in Figs. 4 and 5 on an enlarged scale, the four deflecting plates being made alike. Each of the deflecting plates consists of a flat sheet, and the two plates of each pair are so mounted that they diverge from each other in the direction of the cathode ray beam that passes between them.

The upper and lower edge of each plate is bent 20 inwardly as shown at 25 and 26, thus leaving rounded corners 27 and 28 that are smooth and free from burrs. The side of each plate 17 is bent at right angles to form long flanges 29 and 30, thus producing rounded edges 31 and 32 that are 25 free from burrs. The flanges 29 and 30 have grooves 33 and 34 formed therein to receive the metal rods 1 and 20 to which they are spot welded; and similarly for the three other plates and corresponding rods.

30 In view of the fact that the upper and lower edges of the plate 17 are provided with the flanges 25 and 26, the danger of this plate being accidentally cupped or curved transversely is obviated, and the flanges 29 and 30 prevent cupping or curvature of the plate in the other direction so that the surfaces of the plates that face each other are maintained straight, and in addition the supports for the plates keep them spaced a fixed distance apart as well as maintaining the angle of slope between the plates from varying.

35 What is claimed is:

1. A deflecting plate for a cathode ray tube having edges thereof bent at an angle thereto, said edges having grooves therein for receiving 40 mounting members.

2. A deflecting plate for a cathode ray tube having edges thereof bent at an angle thereto, said edges having grooves therein for receiving 45 mounting members, the axes of said grooves being at predetermined angles to the face of said plate.

ROBERT E. RUTHERFORD.
